CLAIM

The ornamental design for a bag, as shown.

DESCRIPTION

FIG. 1 is a front elevational view of an unfilled bag showing our new design;

FIG. 2 is a top plan view of the unfilled bag of FIG. 1;

FIG. 3 is a side elevational view of the unfilled bag of FIG. 1;

FIG. 4 is a bottom plan view of the unfilled bag of FIG. 1;

FIG. 5 is a rear elevational view of the unfilled bag of FIG. 1;

FIG. 6 is a top plan view of the bag in a filled condition and a closed position;

FIG. 7 is a front elevational view of FIG. 6;

FIG. 8 is a right side elevational view of FIG. 6; the undisclosed opposite side being a mirror image of side shown;

FIG. 9 is a rear elevational view of FIG. 6;

FIG. 10 is a bottom plan view of FIG. 6; and,

FIG. 11 is a rear perspective view of FIG. 1.
